UNITED STATES PATENT OFFICE.

WILLIAM MILL BUTLER, OF PHILADELPHIA, PENNSYLVANIA.

COMBINED BOOK-COVER AND PINCUSHION.

SPECIFICATION forming part of Letters Patent No. 667,495, dated February 5, 1901.

Application filed April 24, 1900. Serial No. 14,127. (No model.)

To all whom it may concern:

Be it known that I, WILLIAM MILL BUTLER, a citizen of the United States, and a resident of Philadelphia, in the county of Philadelphia and State of Pennsylvania, have invented 5 a new and Improved Combined Memorandum-Book and Pincushion, of which the following is a full, clear, and exact description.

The purpose of this invention is to provide 10 a convenient means for carrying pins, such means being especially adapted to use by men. In attaining this end I provide a notebook, such as men usually carry, with pin-receptacles, in which pins may be conveniently 15 stuck and carried. The said receptacles are formed of flexible material folded upon itself and arranged as hereinafter described.

Reference is to be had to the accompanying 20 drawings, forming a part of this specification, in which similar characters of reference indicate corresponding parts in both views.

Figure 1 is a perspective view of the invention. Fig. 2 is an enlarged section thereof. 25 Fig. 3 is a perspective view with parts broken away to show a slightly modified form of the invention.

The covers *a* of the book are rigid and enclose the leaves *b* in the usual manner. They 30 are provided, preferably at their top and bottom edges and at their side edges also, if de-

sired, with sections of leather, which are folded, as shown, the edge or fold proper being perforated to allow insertion of pins. The folded edge is exposed, so that the pins (indicated at *d*) may be easily placed therein. 35

Having thus described my invention, I claim as new and desire to secure by Letters Patent—

1. As an improved article of manufacture, 40 the memorandum-book having covers provided with an inserted strip of flexible material which is doubled or folded upon itself, the fold being perforated and exposed at the edges of the cover, as shown and described. 45

2. As an improved article of manufacture, the memorandum-book having covers whose outer and inner portions are each continuous, or in one piece, around the back, and an inserted piece of leather which is similarly continuous, and folded or doubled upon itself, the fold being provided with perforations and exposed at the edge of the covers proper, as shown and described. 50

In testimony whereof I have signed my 55 name to this specification in the presence of two subscribing witnesses.

WILLIAM MILL BUTLER.
